(57) **CLAIM**

The ornamental design for a display screen with graphical user interface, as shown and described.

DESCRIPTION

FIG. 1 is a front view of the first image in the sequence for a display screen with graphical user interface showing a first embodiment of the new design;

FIG. 2 is a front view of the second image of the first embodiment thereof;

FIG. 3 is a front view of the third image of the first embodiment thereof;

FIG. 4 is a front view of the fourth image of the first embodiment thereof;

FIG. 5 is a front view of the fifth image of the first embodiment thereof;

FIG. 6 is a front view of the first image in the sequence for a display screen with graphical user interface showing a second embodiment of the new design;

FIG. 7 is a front view of the second image of the second embodiment thereof;

FIG. 8 is a front view of the third image of the second embodiment thereof;

FIG. 9 is a front view of the fourth image of the second embodiment thereof; and,

FIG. 10 is a front view of the fifth image of the second embodiment thereof.

The dot-dash perimeter illustrates a display screen and forms no part of the claimed design.

The remaining broken lines illustrate portions of a graphical user interface and form no part of the claimed design.

The appearance of the transitional image sequentially transitions between the images shown in FIGS. 1-5 in the first embodiment, and FIGS. 6-10 in the second embodiment. The process or period in which one image transitions to another forms no part of the claimed design.

1 Claim, 6 Drawing Sheets
